UNITED STATES PATENT OFFICE

ALWIN G. STEINMAYER, OF MILWAUKEE, WISCONSIN, ASSIGNOR, BY MESNE ASSIGNMENTS, TO LINE MATERIAL COMPANY, OF SOUTH MILWAUKEE, WISCONSIN, A CORPORATION OF DELAWARE

FUSE

Application filed May 4, 1928. Serial No. 275,146.

This invention relates particularly to fuses of the expulsion type in which the fuse cartridge is carried by the hinged cover of a fuse box to be disconnected from the line terminals when the cover is opened and has as a primary object the provision of contacts so constructed as to permit perfect seating thereof in their respective clips.

Another object of this invention resides in the provision of a fuse of the character described in which one of its contacts is square and the other round whereby the contacts readily adjust themselves within their respective clips to insure a perfect electrical contact.

15 A further object of this invention resides in the provision of a fuse of the character described in which one of its contacts is threaded onto a tube carried part to impinge the fuse element therebetween, the position of rest of 20 the contact, with respect to the tube, varying depending on the thickness of the element, and the other or fixed contact being round to permit the contacts to adjust themselves with their respective clips to insure a good electrical contact.

With the above and other objects in view which will appear as the description proceeds, my invention resides in the novel construction, combination and arrangement of 30 parts substantially as hereinafter described and more particularly defined by the appended claims, it being understood that such changes in the precise embodiment of the hereindisclosed invention may be made as 35 come within the scope of the claims.

In the accompanying drawing, I have illustrated one complete example of the physical embodiment of my invention constructed according to the best mode I have so far devised 40 for the practical application of the principles thereof, and in which:

Figure 1 is an elevational view of the inner face of a fuse box cover with my improved fuse mounted thereon, parts thereof being 45 broken away and in section, and

Figure 2 is a cross sectional view taken through Figure 1 on the plane of line 2—2.

Referring now more particularly to the accompanying drawing, the numeral 5 designates the cover of a fuse box, not shown,

which is hingedly connected therewith by pivot pins 6 extending from its sides at its lower end and which has suitably secured thereto a pair of spaced, substantially U shaped clips 7 and 8, by which a fuse 9 is 55 detachably mounted on the cover to be connected with line terminals carried by the fuse box (not shown) the terminals engaging the clips 7 and 8 when the cover is closed. The clip 7 has an auxiliary clip 10 positioned 60 therein, the sides or arms of which having a portion thereof arcuately shaped, as at 11.

The fuse which in the present instance is of the expulsion type consists of a tube of insulating material 12 having a contact 13 secured 65 at its upper end which is round in transverse section with flanges 14 at its upper and lower ends and is provided with an upwardly extended exteriorly threaded portion 15 on which a cap member 16 is threaded, a fuse element 17 having one end impinged between the 70 end of the portion 15 and the cap 16 being positioned within the tube.

The element 17 extends downwardly 75 through the tube, passes outwardly of the lower end thereof and is directed upwardly along the outer face of the tube to have its extreme end 18 electrically connected with a contact 19. The contact 19 is tubular with the major portion of its outer periphery 80 square in cross section, and has its upper portion threaded onto a flange 20 formed on a collar 21 which is suitably secured to the tube at a point spaced from its adjacent end. The lower portion of the collar 21 is taperingly reduced, as at 22, and the contact 19 is provided with an inwardly extended flange 23 which is correspondingly taperingly bored, as at 24, to provide parallel tapered faces which approach each other as the contact 19 is threaded onto the flange 20 to impinge the element therebetween. A groove 25 in the flange 20 permits the end of the element to extend therethrough.

As will be readily apparent, the position 95 of rest of the contact 19, with respect to the tube, after being threaded onto the flange 20 to impinge the fuse element between the tapered faces varies, depending on the thickness of the element; this, however, does not 100

affect the perfect seating of the contacts in their respective clips as but one contact has straight sides, the contact 13 being round to conform with the auxiliary clip 10 readily permits the fuse to adjust itself to form a perfect electrical contact. Longitudinal positioning of the fuse is facilitated by the flanges 14 formed on the contact 13 and which are spaced apart a distance to receive therebetween the clips 7 and 10.

If desired an outer tube 26 having vent apertures 27 may be extended from the contact 19 to enclose the lower portion of the tube and the upwardly directed part of the element 17 as will be readily apparent.

What I claim as my invention is:

1. In a fuse of the character described, a body portion, a substantially round contact secured at one end of the body portion, a contact of substantially polygonal shape in cross section mounted adjacent its other end, the body portion extending through the second mentioned contact and a fuse element connecting the contacts.

2. In a fuse of the character described, a body portion, a contact substantially round in cross section positioned at one end of the body portion, a contact having a pair of parallel sides at the other end of the body portion, the body portion extending through the second mentioned contact and a fuse element connecting the contacts.

3. In a fuse of the character described, a body portion having contact members adjacent each end, a terminal clip engageable with each of said contact members, one of said members having a polygonal clip engaging surface, and the other of said members having a rounded clip engaging surface.

4. In a fuse of the character described, a support, uniform terminal clips spaced apart thereon, a fuse body, contacts thereon adjacent each end for engagement in said clips, said contacts each having a cross-sectional area and configuration different from the other, and a supplemental clip mounted in one of said terminal clips.

5. In a fuse of the character described, a support, uniform terminal clips spaced apart thereon, a fuse body, contacts thereon adjacent each end for engagement in said clips, said contacts each having a cross-sectional area and configuration different from the other, the larger of said contacts having direct engagement with one of said clips, a supplemental clip carried by the other of said terminal clips, and the smaller of said contacts having direct engagement with said supplemental clip.

6. In a fuse mounting, a support, terminal clips thereon, a fuse member, a contact movable thereon and adapted for engagement with one of said clips, a contact fixedly secured to said fuse member for engagement with the other of said clips, said fixed con-

tact having a configuration assuming perfect contact with its clip irrespective of the clip engaging position of said movable contact.

7. In a fuse mounting, a support, terminal clips thereon, a fuse member having a contact movable relative thereto and adapted for engagement with one of said clips, a fixed contact on said fuse member, and means on the other of said clips automatically effecting a perfect contact with said fixed contact irrespective of the clip engaging position of said movable contact.

8. A fuse mounting comprising, an elongated fuse, contacts thereon adjacent each end, a support, terminal clips carried thereby and adapted to engage and retain said fuse contacts, one of said contacts having plane contacting surfaces for engagement with a clip, and cooperative means on the other contact and clip for insuring maximum surface contact therebetween irrespective of the relative positions of said plane surfaced fuse contact and clip.

In testimony whereof I have hereunto af-
fixed my signature.

ALWIN G. STEINMAYER.
